UNITED STATES PATENT OFFICE

FRANK W. YOUNG, OF VERONA, NEW JERSEY

GAME APPARATUS

Application filed September 14, 1927. Serial No. 219,373.

This invention relates, in one of its aspects, to a target and, in another of its aspects, to an amusement device in which the target may be embodied and of the kind requiring an exhibition of skill on the part of the participant and appealing to his interest in the game of baseball.

In the illustrated embodiment the amusement device takes the form of a game adapted for use in amusement parks and places of like character, although it is to be understood that the invention in its broadest aspects is equally applicable for target practice of a serious nature as well as to what may be termed a parlor pastime.

One object of the invention is a target which shall not be mutilated or destroyed by missiles projected thereagainst in any manner and which shall give an indication each time a missile strikes the target which is visible at the point from which the missile is projected. Accordingly, the target is formed of a plurality of separate portions, certain of which may be displaced or caused to disappear from view when struck so that that portion of the target which is still visible will give an indication of the score made by that missile. More particularly, the target is formed of a plurality of concentric rings, lying, respectively, in offset planes, and pivoted with respect to a background, so that the ring struck by the missile and the higher numbered rings are displaced when the target is struck.

Another object of the present invention is a game which involves the skill of the participant in throwing a missile at a target. Accordingly, a bull's-eye target is provided whereof the respective rings are adapted to be struck by a missile of substantially the character and size of a baseball.

A further object of the invention, is a method of scoring for a game of the character described which is based upon the scoring in the game of baseball to take advantage of the interest which a large proportion of the visitors to amusement parks and the like have in that game. To this end the bull's-eye of the target may represent a home run and the outer rings, one, two and three

base hits respectively, and the runner is advanced around the bases dependent upon the hit which has been made.

The invention also seeks a practical instrumentality whereby the foregoing objects may be realized. To this end, there is depicted on a background, the representation of a baseball diamond and centrally of this background there is disposed the target heretofore mentioned. A system of lights is also installed in the background such that the position of the runner at a base may be indicated thereby, as well as the thrown balls which have missed the target, the lighting system being so designed as to require operation thereof by an attendant in order that a degree of activity and enthusiasm be exhibited by the attendant which will be contagious and serve to attract participants.

These and other objects of the invention and the means for their attainment will be more apparent from the following detailed description taken in connection with the accompanying drawings illustrating a preferred embodiment thereof, and in which:

Figure 1 is a view, in front elevation, showing the amusement device according to this invention and the target forming a part thereof.

Figure 2 is a sectional view on the line 2-2 of Figure 1, looking in the direction of the arrows and showing the construction of the target and the means for resetting the same after a shot has been registered.

Figure 3 is a wiring diagram for the indicating lights which may be incorporated in the amusement device.

At the present time, with few exceptions, the targets against which missiles are projected, such as projectiles from rifles, shot from air rifles, or darts or arrows are destroyed at the point where the missile strikes. For instance, for rifle bullets, paper targets are generally used and the bullets pass completely through the target and leave holes. The present invention provides a target which requires no attendants and is not destroyed either wholly or in part when a missile strikes it. At the same time, the dis-

placement of that ring or the bull's-eye which is struck by the missile gives a clear indication of the score made on that shot which is visible at the point from which the missile is projected and simple target restoring devices may be provided actuated from the point where the missile is projected to restore the target to its original position preparatory to the next shot.

As a target per se having wide applicability, reference will first be had to Figure 2 of the drawings and to the front elevation of the target illustrated in Figure 1. The border 5 of the target, that is, that portion in which a missile striking it receives the lowest or no value score is shown as being formed upon a stationary vertical background and this background is shown as formed with a circular hole 6 of a diameter equal to the outside diameter of the first ring 7. Parallel to the background there is shown a plate 8 overlapping the hole 6 in the background 5 and formed with a hole 9 therein of a diameter less than the diameter of the hole 6 in the background 5 and equal to the outside diameter of the next smaller ring 10 of the target.

In the illustrated embodiment two more plates 11 and 12 are shown formed with apertures 13 and 14 respectively, the aperture 13 of plate 11 being equal to the outside diameter of inner ring 15 and the aperture 14 being of a diameter equal to the diameter of the bull's-eye 16 which is represented on a plate 17 having no aperture and lying behind the plate 12. These plates 8, 11, 12 and 17 are mounted upon a single pivot pin 18 by means of hinges 19, and 22, where necessary offset hinges as 20, 21 and 22 so as to be movable or displaceable with respect to the background 5 and are adapted normally to be retained in parallel relationship with each other and with the background 5 by means of a plate preferably yieldable and which may, if desired, take the form of a pliable member 23, such as a rope, secured as at 24 to the rear face of the background 5 above the plates 8, 11, 12 and 17 and having a tendency constantly to retain the plates in vertical relation by means of a weight 25 attached to its lower end. If desired, each plate 8, 11, 12 and 17 may be formed with or carry a guiding device such as a loop 26 through which the rope 23 passes. Obviously, other forms of plate retaining devices may be availed of, such as springs or the like which will normally retain the plates in substantially vertical relation but will yield when a plate is struck by a missile.

If one or more of the plates are knocked down to a horizontal position, as indicated in dotted lines in Figure 2 about the pivot pin 18 they may be restored to vertical position through the instrumentality of any convenient resetting devices actuated from

the point from which the missile was projected. In the illustrated embodiment a reset rope 27 or other pliable member is secured to the plate 17 carrying the bull's-eye 16 and this pliable member 27 may extend forwardly to the point from which the missiles are projected so that, if desired, the individual practicing upon the target may reset the target after each shot and thus require no assistant near the target for that purpose. Obviously for long distance ranges an electrically actuated resetting device may be availed of.

Of course the outside ring has the least value and the smaller or inner rings have increasing values to the center or bull's-eye which has the highest value. It will be readily apparent that the result of each contact of a missile with a target i. e. the displacement of the ring or bull's-eye struck together with all higher valued rings, is readily visible at the point from which the missile has been projected. From an observation of the highest numbered ring still visible after the target has been struck and the portion struck displaced to be invisible it is immediately apparent that the missile struck and knocked down the ring having a value immediately higher than the visible ring.

It will thus be readily appreciated that if the target is composed of indestructible material, that is material which will not be affected adversely by the type of missile used and with the indication of the shot clearly apparent at the point from which the missile is projected that such a target is particularly useful for target practice by a single individual who can thus read the score of each attempt and reset the target without assistance. Thus, where the missile is a baseball, the target may be made of wood, but where the missile is a bullet, the target may be made of iron or sheet-steel of suitable calibre.

Such a target has wide applicability. One such application is illustrated in connection with the amusement device shown in the drawings which is intended to represent a baseball game wherein baseballs are projected against the target and the runs scored are based upon hits made on the target.

The amusement device may take the form of a background say the background 5 of the target previously described which is formed of a vertical plane surface having depicted thereon a baseball diamond 30 including the home plate 31 and first, second and third bases, 32, 33 and 34 respectively.

Centrally of the diamond 30 there is illustrated the target 6-16 hereinbefore described.

Each of the bases 32, 33 and 34 depicted on the background 5 is perforated to form the respective holes 35, 36 and 37 too small for the missile, say a baseball, to pass through,

and electric lights 35', 36' and 37' are preferably disposed behind the respective perforations 35, 36, and 37 to illuminate the base to indicate when a runner is stationed thereat. Also, at some convenient place on the background, as shown in Figure 1 at the upper right-hand corner, four apertures 38, 39, 40 and 41 are provided substantially similar in size to the perforations 35, 36 and 37 in the bases, 32, 33 and 34 behind which lights 38', 39', 40' and 41' are also disposed, the first three of these to wit 38', 39' and 40' being intended to indicate the number of "outs", while the fourth light 41' is intended to represent a "home run."

If desired, an inclined runway 42 may be disposed between the lower edge of the background 5 and the counter or trough disposed at the place from which the ball is thrown, so that balls striking the target 6-16 or background 5 will fall to the incline 42 and roll back to the point from which the balls are thrown. Also, if desired, side walls 43 may be provided to confine the thrown balls within the area defined by the background 5, and thus facilitate the recovery of wild pitches.

A wiring diagram is illustrated in Figure 3 whereby the various lights may be illuminated. Two mains 44 and 45 are illustrated as coming from a source of electrical power 46. One of these mains, say 44, is controlled by a master switch 47 and by a plurality of individual switches 48, 49, 50, 51, 53 and 54 controlling the different lights 35', 36', 37', 38', 39', 40' and 41' behind the background 5. All of the lights are connected electrically to the other main 45 and by separate leads, 55, 56, 57, 58, 59, 60 and 61 in series with the individual switches, 48-54.

In playing the game, the target 6-16 is first arranged as indicated in Figure 2, with the plates 8, 11, 12 and 17 carrying the different rings 7, 10, 15 and the bull's eye 16 in parallel relationship with the background 5, and held in such parallel relationship by means of the weighted rope 23. A participant then throws a ball at the target. Assuming now that he strikes one of the outer rings of the target, say the outermost ring 7, he is accorded a one-base hit, and the switch 48 is closed to energize lamp 35' thus showing a light at first base 32 since by a one-base hit the runner reaches first base.

When ring 7 of the target is struck, it is cause to fall backwardly about its point of pivot 18 against the action of the weighted rope 23 and of course carries with it the remaining and rearwardly disposed plates 11 and 12 and bull's-eye plate 17 to a horizontal position as indicated in dotted lines in Figure 2. The weighted rope 23 is of course displaced as also shown in dotted lines. This affords a positive indication of which

ring was struck since it is obviously the lowest valued ring no longer visible.

After one or more of the rings have been knocked down, it is necessary to restore the rings to original or vertical position, and to this end, the bull's-eye frame 17 connected to the reset rope is drawn back to vertical position by means of the reset rope which is pulled by an attendant.

Assume now that the second thrown ball does not strike any one of the concentric rings. The contestant is then accorded an "out", and the attendant closes the switch 51 to illuminate the light 38' which illuminates the first "out" hole 38 in the upper right hand corner of the background 5.

If the next ball thrown by the contestant strikes ring 10 he is accorded a two-base hit, and the operator closes individual switch 50 to illuminate the third base 34, since the two-base hit has advanced the runner from first base to third base. And now any hit will score a run.

If the third ring 15 is struck signifying a three-base hit, only plate 12 and the bull's-eye plate 17 are knocked down as previously described.

If the bull's-eye 16 is struck, a home run is scored. None of the lights 35', 36', or 37' behind the bases are illuminated, but the light 41' behind the home run aperture 41 is illuminated by closing the home run switch 54.

After the contestant has taken three tries which do not result in scores three outs have been accorded him and he is deprived of his right to continue.

The playing is continued by the contestant until he scores a run or has three outs. The run scored of course entitles him to a prize which is immediately awarded him.

In the playing of this game certain duties devolve upon the attendant. After each ball is thrown, he must reset the target and operate the switches to indicate the hit or "out". These activities induce the operator to a vocal expression of the score being made, and the combination of his calling of the "out" or base hit or home run, plus his movements in operating the switches to indicate the score being made, and to return the target to visible condition and the physical movement of portions of the target lend an atmosphere of enthusiasm to the game which is contagious and serves to attract customers.

It will thus be seen that a game is provided which requires a degree of skill which in itself is an attraction and that the scoring of this game is based upon the scoring in baseball with which practically everyone is familiar and is interested in. The construction of this amusement device is simple, durable, easily and cheaply manufactured, and readily operated.

It will also be seen that an indestructible target is provided which has wide applicability and requires no attendant.

Various modifications may be made in the composition and configurations of the component elements going to make up the invention as a whole, and in its various aspects, as well as in the electric circuits and in the matter of scoring. Furthermore, the target is capable of use independent of the device with which it is shown associated. No limitation is intended by the phraseology of the foregoing description or illustrations in the accompanying drawings except as indicated in the appended claims.

What I claim is:

1. An amusement device comprising a background having depicted thereon a baseball diamond whereof the three bases are formed with apertures of a diameter less than the diameter of a missile, and said background being also formed with a plurality of apertures of substantially similar size in spaced relation with the representation of the baseball diamond for scoring purposes, and said background being formed with a hole centrally of the diamond, a plurality of plates adapted to be disposed in parallel relationship with each other and the background rearwardly thereof, a transverse pivot pin carried rearwardly of the background below the hole therein, connections between the respective plates and the pivot pin, a weighted pliable member secured to the background above the plates and depending therebehind, means to limit the pivotal movement of the plates with respect to said background, all of said plates, but the rearmost, being formed with apertures which decrease in diameter rearwardly, respectively, means to reset the plates in vertical position, electric lamps disposed behind the background behind the respective first and second named apertures, electrical connections with a source of supply and means to selectively energize the respective lamps.

2. An amusement device comprising a background having depicted thereon a baseball diamond whereof the three bases are formed with apertures, and said background being also formed with a plurality of apertures in spaced relation with the representation of the baseball diamond for scoring purposes, and said background being formed with a hole centrally of the diamond, a plurality of plates adapted to be disposed in parallel relationship with each other and the background rearwardly thereof, a transverse pivot pin carried rearwardly of the background below the hole therein, connections between the respective plates and the pivot pin, a weighted pliable member secured to the background above the plates and depending therebehind, means to limit the pivotal movement of the plates with respect to said

background, all of said plates, but the rearmost, being formed with apertures which decrease in diameter rearwardly, respectively, means to reset the plates in vertical position, signal means disposed behind the background behind the respective first and second named apertures, and means to selectively actuate the respective signal means.

In testimony whereof I affix my signature.
